Patented May 23, 1922.

INVENTOR

PHILIP H. NOLTING,
James D. Hopkins,
ATTORNEY.

UNITED STATES PATENT OFFICE.

PHILIP H. NOLTING, OF ST. LOUIS, MISSOURI.

SHIRT.

1,417,101.

Specification of Letters Patent. Patented May 23, 1922.

Application filed July 16, 1919. Serial No. 311,300.

To all whom it may concern:

Be it known that I, PHILIP H. NOLTING, a citizen of the United States, residing at St. Louis and State of Missouri, have invented certain new and useful Improvements in Shirts, of which the following is a specification, reference being had therein to the accompanying drawing.

My invention relates to improvements in shirts, and has for its object to provide an outer shirt, with a skirt buttoning upon itself to form drawers.

In the drawings—

Fig. 1 is a front elevation of the shirt of my invention.

Fig. 2 is a diagonal view of the same.

Fig. 3 is a rear elevation of the same.

Fig. 4 is a fragmental view of the lower edge of the skirt of the garment, indicating the manner in which the back section thereof is gored to receive a crotch-piece.

Fig. 5 is a plan view of the crotch-piece.

As shown in the drawings, the shirt 6 is of the ordinary construction of an outer shirt, of the type generally styled "coat shirt"; the shirt opening on the front along the line 7, and being kept closed by buttons 8.

The back section 9 is provided with a gore 10, as illustrated in Fig. 4, and in said gore 10 the crotch-piece 11 is sewed, its edge 12 being stitched to the edge of said gore 10. Said crotch-piece 11 is substantially rectangular in form as shown in Fig. 5, and its lower or free edge is provided with a central button-hole 13 whereby said crotch-piece 11 is secured to the button 14; other button-holes 15 are secured to buttons 16 as shown, thus causing the garment to fit around the legs of the wearer to serve as drawers.

The lower portion of the front of the shirt 6 has a left flap or section 17 secured vertically to the meeting edge of the back 9, along the line 18. The right flap or section 19 is secured to the right edge of the back 9 by buttons 20, so that the drawers-portion of the garment, may be opened at the right side by unbuttoning the buttons 20 by leaving the crotch-piece 11 in closed or buttoned position, as shown in Fig. 1. The button 14 engages with the button-hole 21 of the flap 17, before entering and engaging with the button-hole 13.

The garment thus described enables its wearer to dispense with the use of undergarments, although admitting the use of an under-shirt, if desired. The garment is so formed as to afford comfort to the wearer. By its use the wearer is enabled to save the cost of underwear, and to save the expense of laundering such underwear.

Having thus described my invention what I claim as new and desire to have secured to me by the grant of Letters Patent, is—

The improvement in shirts comprising a coat-shirt having a back section provided with a gore; a substantially rectangular crotch-piece secured at its rear edge to the edge of said gore; and having a central and side button-holes along its free edge; two front flaps extending downwardly from the front of the shirt, one of said flaps being permanently secured to the back section and the other of said flaps being secured to the meeting edge of the back sections by buttons and so arranged to be opened while leaving the crotch-piece in closed position.

In testimony whereof I hereunto affix my signature.

PHILIP H. NOLTING.
